UNITED STATES PATENT OFFICE.

WILLIAM ROHM, OF APPLETON, WISCONSIN.

BUILDING CONSTRUCTION.

1,125,721.

Specification of Letters Patent.

Patented Jan. 19, 1915.

Application filed March 9, 1914. Serial No. 823,420.

To all whom it may concern:

Be it known that I, WILLIAM ROHM, a citizen of the United States, residing at Appleton, in the county of Outagamie and State of Wisconsin, have invented certain new and useful Improvements in Building Construction, of which the following is a specification, reference being had to the accompanying drawing.

10 This invention relates to silos with outer and inner walls and building blocks therefor, and has for its object the production of means for facilitating the securing of said blocks in an assembled position.

15 Another object of this invention is, the production of an efficient door jamb for a silo or other building, that is composed of an outer and inner wall.

With these and other objects in view, this 20 invention consists of certain novel constructions, combinations and arrangements of parts as will be hereinafter fully described and claimed.

Figure 1 is a horizontal section taken 25 through the silo. Fig. 2 is an elevation of a part of the wall and door of the silo. Fig. 3 is another horizontal section of a part of the wall and the door. Fig. 4 is a vertical and transverse section through the 30 wall. Fig. 5 is an elevation partly in section of one of the door jambs. Fig. 6 is a section through the door way upon the line a, a , of Fig. 1, looking toward the left. Fig. 7 is a plan of one modification of the 35 door jamb blocks. Fig. 8 is a plan of a bracket which is applied to the separate door sections. Figs. 4, 5, 6, 7 and 8, are upon an enlarged scale from the previous figures.

40 Similar numerals and letters indicate like parts in the several views.

The silo is constructed of a plurality of blocks A and B, for the outer and inner walls 1 and 1^a , respectively, the blocks being 45 formed of burned clay, cement and sand or other material mixed in a liquid state and allowed to dry, that has the requisite strength. These blocks are provided upon their upper and lower faces with semicircular grooves 50 8, in which grooves tie rods 7 are adapted to be placed longitudinally of the blocks. This reinforcing rod extends through the grooves in all the blocks A and B, and into the grooves 8^a , in the blocks 2, 3, 10 and 11, 55 at the door way, as clearly shown in Figs. 1 and 3. The usual mortar or other plastic

substance may be used between the blocks for holding the same in a congested mass, and thereby firmly holding the reinforcing rods 7 in position within the grooves. The 60 blocks 3 have the special shape shown with rabbets 4^a , for the door 4, and a semicircular groove 8^a , in their upper and lower faces for receiving the semicircular bends of the reinforcing rods 7, also, a vertical 65 perforation 6, for a pin 9 and a recess 5^a , for a tie rod 5. The block 3 is of such form that it not only forms the door jamb, but it also connects the outer and inner walls 1 and 1^a , with each other with the central 70 air space 12 between them. The blocks 2 are similar to blocks 3 excepting that they have two extensions fitting the outer and inner walls, the object of which extensions being to break the vertical joint when superposed upon block 3. Blocks 10 and 11 are a modified form for the door way from the blocks 2 and 3. Block 10 is similar to block 3, excepting it has an extension for the inner wall, while block 11, has an extension 75 for the outer wall, these extensions forming the break in the vertical joints for superposed blocks. By turning block 11 bottom side up upon block 10, it will break joints with it.

The tie rod 5 may be made of a suitably shaped metallic rod of the required strength, and its ends so formed as to connect over the reinforcing rods 7 in the recesses 8^a , in blocks 2, 3, 10 and 11. These tie rods can 90 be placed between alternate courses as shown, and which will be sufficiently near together usually, or be placed any number of courses apart, according to the required strength. The door may be secured to the 95 tie rods if so desired. The vertical pin 9, may be used in all joints between the door jamb blocks, when the tie rod is not used, but its use may not be necessary in all cases.

From the foregoing description, it will be 100 seen that the entire construction of the silo will be firmly and rigidly tied and bonded together through the combined use of the special blocks, tie rods and mortar. Of course the several blocks are to be formed 105 in accordance with the form of building wherein they are to be used.

In the present case the blocks are slightly curved as shown, to conform to a substantially circular building. The door is formed 110 in sections, vertically, and may be in length substantially from one tie rod to another,

and be formed of two thicknesses of boards 13 and 14, fitted to the rabbets 4^a in the door jambs. The outer boards may extend an inch or so below the boards of the inner ones, excepting in the lower section, for forming a recess 15, for receiving the outer course of boards of the door section above it. A threshold 16, formed of cast iron and provided with a flange along its inner edge 10 of a width about equal to the width of the rabbet 4^a, is placed under the lower course of door jamb blocks for the lower edge of the door to shut against. This flange, 17, may be arranged under the outer course of 15 door boards as in Fig. 6, or abut the outside course as in Fig. 3. The doors may be formed of but one thickness of boards and be provided with battens 18, as in the lower door section in Fig. 2.

20 The tie rods 5 are preferably spaced apart the distance of the thickness of two courses of blocks and with say 10 inch blocks, it makes the spaces between tie rods too long when the tie rods are used as ladder rounds 25 for ascending the silo walls. To obviate this long stretch between ladder rounds, I make the door sections to meet at a point just above a rod 5, and connect it with said rod with a hook 19, in a well known manner, and midway between two tie rods attach 30

an angular bracket rod 20, having a fixed collar 21 and screw nut 22 to said door section, the part of the bracket that lies parallel with the rods 5 being in the same vertical plane as the rods, and thereby forming 35 an easily ascended ladder, while the bracket serves also as a handle with which to lift the door.

Having described my invention, what I claim and desire to secure by Letters Patent, is,—

In a building composed of blocks laid in courses, an outer and inner wall and an air space between them, a door way opening from the bottom to near the top of the building walls, special shaped door jamb blocks, a groove upon the upper and lower face of each block and a curved groove in the upper and lower face of each door jamb block registering with the grooves in the main 50 wall blocks, a continuous rod arranged in the grooves of the outer and inner wall and door jamb blocks and a rod extending across the door way and being connected to the curved ends of said continuous rod.

WILLIAM ROHM.
